FIG. 3.

Inventor:

J. L. CRACRAFT,

By *H. J. Fitzgerald & Co.*

Attorney.

UNITED STATES PATENT OFFICE.

JULIAN L. CRACRAFT, OF GEORGETOWN, KENTUCKY.

ELEVATING BAGGAGE TRUCK.

Application filed April 17, 1922. Serial No. 553,797.

To all whom it may concern:

Be it known that I, JULIAN L. CRACRAFT, a citizen of the United States, residing at Georgetown, in the county of Scott and 5 State of Kentucky, have invented certain new and useful Improvements in Elevating Baggage Trucks; and I do hereby declare the following to be a full, clear, and exact 10 description of the invention, such as will enable others skilled in the art to which it appertains to make and use the same.

The present invention relates to trucks such as are used for conveying baggage or other objects from one place to another, and 15 aims to provide a novel and improved truck having means for elevating the load for the convenient loading and unloading of the truck.

Another object of the invention is the provision of such a truck having novel and improved means between the wheel-mounted frame and the top or deck for raising said deck in a simple, practical and efficient manner to elevate the load.

25 With the foregoing and other objects in view, which will be apparent as the description proceeds, the invention resides in the construction and arrangement of parts, as hereinafter described and claimed, it being understood that changes can be made 30 within the scope of what is claimed, without departing from the spirit of the invention.

The invention is illustrated in the accompanying drawings, wherein—

35 Figure 1 is a side elevation of the truck with the deck or platform in lowered position.

Fig. 2 is a horizontal section on the line 2—2 of Fig. 1.

40 Fig. 3 is a side elevation showing the deck raised.

In carrying out the invention, there is provided a suitable frame 7 mounted on the wheels 8, and having the transverse end 45 bolsters 9. The top or deck 10 has transverse bolsters 11 at the under side thereof to seat on the bolsters 9 when the deck is in lowered position, as seen in Fig. 1.

The elevating device includes a pair of 50 levers or arms 12 pivotally or hingedly connected to bearings 13 secured to each bolster 9 at the inner side thereof. The levers at the opposite ends project toward one another, and said levers are provided at their 55 free ends with rollers 14 to bear against the

lower surface of the deck or top 10, whereby the levers in being swung upwardly, will raise the deck, such rollers reducing the friction between the levers and deck and providing for a free and easy motion. 60

In order to swing the levers 12 for raising and lowering the deck, a longitudinal shaft 15 is journaled through the bolsters 11 and through cleats or bearings 16 secured to the lower surface of the deck between the bolsters 11, and collars 17 are secured to the shaft at the opposite sides of said bolsters 11 and bearings 16, for retaining the shaft against longitudinal movement. The shaft is thus carried by the deck underneath same, and is formed with the reverse screw-threads 18 between the bolsters 11 and adjacent bearings 16. A transverse bar or cross head 19 is disposed between each pair of levers 12 and has a nut portion 20 between 75 its ends threadedly engaging on the corresponding screw 18, whereby the rotation of the shaft 15 will move the cross heads 19 in opposite directions in view of the fact that the screws are reversed. The terminals 80 of the cross heads 19 have portions 21 working within longitudinal slot 22 in the levers 12, providing slidable and pivotal connections between the cross heads and levers.

The shaft 15 is rotated by any suitable 85 means, such as a hand crank 23 attached to one end thereof.

The truck can be conveniently loaded with the deck 10 in lowered position, and in order to conveniently unload the truck at a higher 90 level, the deck is raised. In order to raise the deck, the shaft 15 is rotated in the proper direction to move the cross heads 19 toward the bolsters 11, whereby the portions 21 of the heads in working in the 95 slots 22 will swing the levers 12 upwardly, and the rollers 14 in travelling under the deck, will raise said deck. The levers 12 can be brought to a vertical position, as seen in Fig. 3, to support the deck in its 100 highest position, with the cross heads 19 adjacent to or bearing against the bolsters 11. By reversing the rotation of the shaft 15, the cross heads are moved away from the bolsters 11, thereby lowering the deck until 105 it seats on the frame 7.

Having thus described the invention, what is claimed as new is:—

A truck comprising a wheel-mounted frame, a deck above said frame, two 110

pairs of levers hingedly connected to the frame and having portions contacting with and movable along the lower surface of the deck, a shaft carried by and mounted under the deck and located between the levers of the two pairs, and cross heads threadedly mounted between their ends on said shaft, said levers having elongated slots slidably receiving the end portions of said 10 cross heads, the deck being supported di-

rectly on said levers when the levers are swung upwardly.

In testimony whereof I have signed my name to this specification in the presence of two subscribing witnesses.

JULIAN L. CRACRAFT.
